UNITED STATES PATENT OFFICE.

JOSEPH A. READ, OF PHILADELPHIA, PENNSYLVANIA.

IMPROVEMENT IN STOVE-GRATES.

Specification forming part of Letters Patent No. **174,641**, dated March 14, 1876; application filed January 19, 1876.

To all whom it may concern:

Be it known that I, JOSEPH A. READ, of the city of Philadelphia, in the State of Pennsylvania, have invented a new and useful Improvement in Grates for Stoves, which improvement is fully set forth in the following specification, reference being had to the accompanying drawings.

The object of my invention is to produce a vibratile circular grate for stoves and furnaces, whereby the separation of the ashes and the discharge of cinders or stones are facilitated, and without tilting any portion of the grate.

Figure 1 is a plan view, showing the upper side of my said improved grate; Fig. 2, a plan view of the outer rim of the same without the central portion; Fig. 3, a plan view of the under side of said central portion detached from the said outer portion, and Fig. 4 a vertical diametrical section of the two said parts of the grate adjusted together.

The outer portion or rim A has its flanged portion a' provided with alternating teeth 2 and spaces 3, and is under-curved at 4 (see Fig. 4) to the lower side of the rim, while the inner side a^o of said rim A is beveled outward and upward from the under to the upper sides of said rim, as shown in Figs. 2 and 4. About one-fourth of the area of the opening within the rim A is occupied by a flat sector-shaped plate, a'' , the inner end 5 of which has a circular cavity, 6, (see Figs. 2 and 4,) for supporting the inner grate B by its central boss b' . This sector-shaped plate a'' is perforated by numerous holes, 7, through which ashes may readily pass down into any ordinary ash-pit or drawer. (Not shown.)

The inner grate B is made of such diameter and thickness as will nearly fill the open area of the outer rim A when the central boss b' thereof rests or moves in the cavity 6. The perimeter of B is provided with alternating teeth 8 and spaces 9 around about three-fourths of its circumference. The interior of said grate B is divided by a central hub, b'' , and four arms, 10 10 10 10, into four sector-like spaces, one of which, 11, is entirely open or free from any obstructions, and the other three spaces divided by intervening spaces

and projections, as represented in Figs. 1 and 3.

When the whole grate is at rest and supporting the fuel the open space 11 of the part B is directly over the perforated plate a'' of the part A, and thus the latter prevents the fuel from falling from above it into the usual ash-pit; but when the part B is turned around on its boss b' , so as to bring the open space 11 to one side edge of the plate a'' , the stones, cinders, or fuel can be readily removed through said open space 11, as occasion may require. The whole grate is supported by a downward-projecting conical stem, 12, (see Fig. 4,) which is supported in the usual socket of the ordinary cross-bar, (not shown,) so that the whole grate may be vibrated, as occasion may require.

On the under side of the center-grate B there are two studs or projections, 13 14, near the outer ends of the bars 10' 10'', respectively, (see Figs. 3 and 4,) which serve, alternately, to stop the vibrative motions of said grate B by coming in contact with the outer edges of the plate a'' of the grate A, and thus limit the vibrative motions of the center-grate B in the operation of opening and closing the space 11 therein. Through the curved edge of the grate A there is a hole, 15, for the insertion of the end of a shaking bar or handle, (indicated by the dotted lines v in Fig. 1,) and directly opposite to this hole 15 there is a mortise or corresponding hole in the thickened edge 16 of the center-grate B, so that the end of the handle may be entered into both holes when it is desired that both A and B shall be vibrated simultaneously in shaking out the ashes; and so, also, that the entering end of said handle v may be withdrawn from the mortise in B, and allow the outer grate A to be moved around the center-grate B (which will be held stationary by the fuel or burden upon it) for the purpose of producing the required opening for the discharge of cinders, stones, or the whole contents of the fuel or fire box down into the usual ash-pit or drawer. (Not shown.)

Having thus minutely described and explained the construction and operation of the different parts of my improvement in stove-

grates, it will be readily understood and appreciated without any further remarks.

I claim as my invention—

A circular grate, consisting of the rim or outer portion A, and its plate a" and handle-hole 15, in combination with the central portion B having the open space 11 and mortise 16, the said parts being constructed and ar-

ranged to operate together substantially in the manner hereinbefore set forth and described.

JOSEPH A. READ.
